Mathias Berres INVENTOR.

BY
 S. S. Thomas
 ATTORNEY.

UNITED STATES PATENT OFFICE.

MATHIAS BERRES, OF HAMTRAMCK, MICHIGAN.

COMBINED SHOULDER-BRACE AND TROUSERS-SUPPORTER.

1,377,387.

Specification of Letters Patent. Patented May 10, 1921.

Application filed September 29, 1920. Serial No. 413,495.

To all whom it may concern:

Be it known that I, MATHIAS BERRES, citizen of the United States, residing at Hamtramck, county of Wayne, State of Michigan, have invented a certain new and useful Improvement in Combined Shoulder-Braces and Trouser-Supporters, and declare the following to be a full, clear, and exact description of the same, such as will enable others skilled in the art to which it pertains to make and use the same, reference being had to the accompanying drawings, which form a part of this specification.

My invention relates to a combined shoulder brace and trousers supporter, shown in the accompanying drawings and more particularly described in the following specification and claims.

One of the objects of my invention is to provide a simple and effective adjustable shoulder brace adapted to support the trousers, which may be engaged thereto at the waist line (the usual buttons on the waistband of the trousers being eliminated) by means adapted for adjustment to insure the proper "hang" of the trousers that they may present a "smart," neat and trim appearance.

A further object of the invention is to provide for the adjustment of the device that it may be adapted for persons of varying waist measurements.

A further object is to provide for the adjustment of the strap comprising the shoulder brace whereby it may be adapted for men of different stature.

A further object is to provide a device which will induce deep breathing, expand the chest, force the wearer to stand and sit erect and which will at the same time be comfortable to wear.

A further object is to provide a device which may be worn above or beneath the shirt as may be desired.

With the foregoing and other objects in view which will appear as the description proceeds, the invention further consists in the combination and arrangement of parts and in the details of construction herein-after described and claimed, it being understood that changes may be made in the precise embodiment of the invention herein

shown without departing from the spirit of the same.

In the drawings forming part of this specification:—

Figure 1 is a view showing the manner of adjusting the device beneath the arms of the wearer before connecting the ends of the strap or brace with the trousers.

Fig. 2 is a similar view showing the shoulder brace in position and connected with the trousers.

Fig. 3 is a perspective view of that portion of the device connected with the trousers.

Fig. 4 is a vertical cross-sectional view through the U-shaped element connecting the strap with the metallic trouser bands.

Fig. 5 is a cross-sectional view taken on or about line 5—5 of Fig. 3.

Referring now to the letters of reference placed upon the drawings:—

A, denotes a belt or strap of suitable length that it may pass across the back beneath the arms, thence in a forward and upward direction over the shoulders to the back of the wearer where it overlaps itself; the ends being fitted with means for attachment to the trousers B.

C, C, indicate a pair of arc-shaped members adapted to overlap a portion of their length, formed with interlocking indentations or ribs C', C', for purpose of adjustment,—the parts being secured in their adjusted position by clips D, D, embracing the abutting portions of said members.

E, E, are inverted U-shaped elements detachably secured to the free end of the arc-shaped members C, and to the waist band of the trousers by spring clips F, spaced from the ends of the elements E to admit between the same, the member C, and the waist band of the trousers. F', is a swinging lever arm, pivoted to lugs integral with the member E, having an offset portion F² adapted to force the spring clips F to impinge upon the trouser band so as to grip the latter and the arc-shaped members C.

The ends of the U-shaped elements E, E, are each provided with projecting pins or studs E', designed to enter any of a plurality of holes C² in the free ends of the arc-shaped members C, C, that the elements

E, E, may be securely held against displacement when properly adjusted to fit the wearer. E² is a slot formed in an upper extension of the elements E, E, to receive a 5 detachable strap or loop G, connecting said elements with a slidable double loop H, carried in a loop A', formed by a return bend of the strap A. A² is a slidable buckle secured to the end of the strap A for adjusting 10 the length of the strap to the wearer.

Having indicated the several parts by reference letters it will be apparent that the device when properly adjusted as shown and described will serve to remind and will assist the wearer to secure an erect carriage, 15 to expand the chest, and in addition will support the trousers so that they may present a neat appearance at all times.

Having thus described my invention what 20 I claim is:

1. In a device of the character described, a strap of suitable length to adapt it to cross the back of the wearer beneath the arms pass over each shoulder to the back and thence 25 downwardly overlapping itself with its ends extending to the sides of the wearer adjacent to the trouser waist band, a pair of extensible overlapping metallic members adapted to be detachably secured to the waist band 30 of the trousers, means detachable and adjustably secured to said last named members

at each side of the wearer, and detachable means for securing the ends of said strap to the respective last named means.

2. In a device of the character described, 35 a strap adapted to extend horizontally across the back of the wearer, thence over the shoulders, overlapping itself upon the back of the wearer with its ends extending downwardly toward the sides of the wearer adjacent to the trouser waist band; a pair of arc-shaped co-acting, metallic members adapted to overlap each other, the overlapping portions indented to interlock; means 40 for securing said members together when interlocked; a pair of inverted U-shaped members provided with projecting studs adapted to enter any of a plurality of holes in the free ends of the arc-shaped members, whereby the U-shaped members may be adjusted 45 laterally with reference to the arc-shaped members; spring clips carried by the U-shaped members adapted to grip the trouser-band to the arc-shaped members; and detachable means for connecting the U-shaped 50 members to the ends of the strap.

In testimony whereof, I sign this specification in the presence of two witnesses.

MATHIAS BERRES.

Witnesses:

S. E. THOMAS,
CHAS. F. CARNEY.
